UNITED STATES PATENT OFFICE

2,669,707

FILTER SIGNAL

Frederick S. Ehrman, Fort Wayne, Ind., assignor
to Bowser, Inc., Fort Wayne, Ind., a corporation
of Indiana

Application April 29, 1950, Serial No. 159,053

4 Claims. (Cl. 340—239)

1

This invention relates to a filter signal. More specifically, it relates to a signal which is displayed when the filter requires attention.

It is a well known fact that filters employing a filter cartridge, such as those used for cleaning the crank case oil of internal combustion engines, become plugged and become inoperative. There is nothing to indicate when this occurs so that the engine may operate without the benefit of filtration until someone thinks to change the filter.

It is an object of the invention to provide means for signalling the operator when the filter is plugged to the extent that liquid is being bypassed around the filter.

Another object of the invention is to provide a signal which is simple and inexpensive.

A further object is to provide a signal which may be reset when the cartridge has been changed.

These and other objects will become apparent from a study of this specification and the drawing which is attached hereto and made a part hereof, and in which:

The single figure is an elevation in section with parts broken away to show the by-pass valve.

The numeral 1 represents a filter case having an inlet 3 and an outlet 5. The case is in two parts 6, 7 which have mating flanges 9, 11 held together by suitable fasteners 13.

The outlet in part 7 is provided with a suitable outlet tube 15 on which a head 17 is slidably mounted and sealed by a ring 18 disposed in groove 20.

The part 6 is provided with a fitting 19 having a stem 21 screwed into it. This stem includes a projection 23 which enters and guides the upper head 25, and a shoulder 27 which bears on a gasket 29 to seal the upper head and stem.

A filter cartridge 30 of any suitable type is sealingly held between the heads, preferably by a spring 31.

The projection 23 has a passage 33 which communicates at its upper end with an inlet passage 35 in the stem and at its lower end with a by-pass chamber 37.

A magnet chamber 39 is formed in the stem above passage 33, preferably in axial alignment with 33 and 37, and has its lower end closed by a non-magnetic diaphragm 41. The stem is preferably also non-magnetic.

A valve 43 is mounted in valve chamber 37 and has a stem 45 which projects through passage 33 to a point closely adjacent the diaphragm where it terminates in an armature 47 disposed

parallel to and closely adjacent the diaphragm. A spring 49, disposed in the chamber 37, rests on a pin 51 and urges the valve 43 closed.

A magnet 53 is slidably mounted in the chamber 39 and has a rod 55 which extends outwardly through the stem and supports at its upper end the signal button 57. A spring 59 which bears on the stem and button normally urges the button, rod and magnet upwardly.

A housing 61 having sight openings 63 which may be covered by a transparent insert tube 65, enable the position of the indicator button to be determined. This housing may be frictionally engaged with a boss 67 on the stem.

Operation

Liquid entering the inlet 3 normally passes through the filter cartridge and out the outlet tube 15 and outlet 5. When the filter becomes substantially impervious due to the accumulation of impurities removed from the liquid, the liquid will by-pass the cartridge by entering conduits 35, 33, will displace the valve 43 against the opposition of spring 49 and pass through chamber 37, tube 15 to outlet 5.

When the valve is thus displaced, it will draw the armature away from magnet 53 so as to reduce the force holding the magnet in place. The spring 59 overcomes this force and moves the magnet, rod 55 and signal 57 upwardly so that the latter is visible in the windows 63.

The operator perceiving the signal, knows that the cartridge should be replaced. He then shuts the required valves (not shown), removes the fasteners 13 and cover 6, removes head 25 and the filter cartridge. He will then replace the cartridge with a clean one, replace the parts mentioned above and the filter is again ready for operation. He will next remove the housing 61, push the indicator down until the magnetic force on the armature is great enough to overcome the spring 59 so that the indicator will be held down out of sight.

The valves may be opened and the filter restored to service.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claims.

What I claim to be new and desire to protect by Letters Patent of the United States is:

1. In a filter comprising a filtering medium, the

3

combination of a signal having ineffective and signalling positions, means for urging said signal toward signalling position, means normally holding said signal in ineffective position, a normally closed valve means, disposed so as to be opened by the increase in pressure resulting from substantial clogging of the medium, for by-passing liquid around said medium, and means operated by said valve means for releasing said holding means.

2. In a filter comprising a filtering medium, the combination of a signal having ineffective and signalling positions, means for urging said signal toward signalling position, means normally holding said signal in ineffective position, a normally closed valve means, disposed so as to be opened by the increase in pressure resulting from substantial clogging of the medium, for by-passing liquid around said medium, an armature connected to be operated by said valve means, a magnet, a signal mounted for movement between ineffective and signalling positions, means urging said signal toward signalling positions, said armature being disposed closely adjacent the magnet, when the valve is closed, so that the magnetic force will overcome the urging means and being connected to be moved away from said magnet when the valve is opened so that the urging means will overcome the magnetic force.

3. In a filter comprising a filtering medium, the combination of a signal having ineffective and signalling positions, means for urging said signal toward signalling position, means normally holding said signal in ineffective position, a normally closed valve means, disposed so as to be opened by the increase in pressure resulting from substantial clogging of the medium, for by-passing liquid around said medium, an armature connected to be operated by said valve means, a magnet, a non-magnetic diaphragm disposed between the armature and magnet, a signal mounted for movement between ineffective and signalling positions, means urging said signal to-

4

ward signalling position, said armature being disposed closely adjacent the magnet, when the valve is closed, so that the magnetic force will overcome the urging means and being connected to be moved away from said magnet when the valve is opened so that the urging means will overcome the magnetic force.

4. In a filter comprising a filtering medium, the combination of a signal having ineffective and signalling positions, means for urging said signal toward signalling position, means normally holding said signal in ineffective position, a normally closed valve means, disposed so as to be opened by the increase in pressure resulting from substantial clogging of the medium, for by-passing liquid around said medium, a signal mounted for movement between ineffective and signalling positions, a magnet and an armature mounted closely adjacent each other for movement with said valve and signal, means mounting said valve means for movement, and means operated by the valve to separate said armature and magnet, means for urging said signal toward signalling position, said urging means exerting less force than said magnet and armature when the latter are in close proximity and exerting greater force than the magnet and armature when the latter are separated by a predetermined amount, whereby said signal is moved to signalling position when the valve means is moved a distance sufficient to separate said armature and signal by said amount.
